UNITED STATES PATENT OFFICE.

AARON W. DAVIS, OF NEW YORK, N. Y., ASSIGNOR TO DAVIS & CATTERALL, INC., OF NEW YORK, N. Y., A CORPORATION OF NEW YORK.

DESIGN FOR A HANDKERCHIEF.

Application filed January 8, 1926. Serial No. 15,999. Term of patent 14 years.

To all whom it may concern:

Be it known that I, AARON W. DAVIS, a citizen of the United States of America, residing at New York, in the county of New York and State of New York, have invented a new, original, and ornamental Design for Handkerchief, of which the following is a specification, reference being had to the accompanying drawing, forming a part thereof.

The figure is a face view of a handkerchief, showing my new design.

I claim:

The ornamental design for a handkerchief as shown.

AARON W. DAVIS.
